UNITED STATES PATENT OFFICE.

WILLIAM M. BURTON, OF CHICAGO, AND EDGAR M. CLARK, OF ALTON, ILLINOIS,
ASSIGNORS TO STANDARD OIL COMPANY, OF WHITING, INDIANA, A CORPORA-
TION OF INDIANA.

PROCESS OF TREATING PETROLEUM OILS.

Application filed March 2, 1916. Serial No. 81,865.

To all whom it may concern:

Be it known that we, WILLIAM M. BURTON and EDGAR M. CLARK, citizens of the United States, residing at Chicago, in the county of Cook and State of Illinois, and Alton, in the county of Madison and State of Illinois, have invented a new and useful Improvement in Processes of Treating Petroleum Oils, of which the following is a specification.

Our invention relates to certain improvements in the art of distilling hydrocarbon oils. More particularly the invention is concerned with the destructive distillation or "cracking" of relatively heavy petroleum oils to produce therefrom lighter oils. The primary object of the present invention is to provide a method of operation by which relatively high cracking temperatures may be obtained, without the usual concomitant condition of proportionately high pressures. By our present process this desirable result is obtained, and likewise numerous secondary advantages of considerable practical importance.

The invention will be more fully understood from the following detailed description taken in connection with the accompanying drawing, in which:—

30 Fig. 1 illustrates diagrammatically in side elevation one form of apparatus for carrying out the process, and Fig. 2 is an enlarged vertical broken section through the still.

35 Referring first to the drawing, the numeral 10 designates the drum of a suitable still, which as illustrated is of the horizontal tubular type, the tubes designated 10', being located within the furnace 11. A stack 12 is connected with the furnace as by an underground flue 13. The external fittings of the still include the usual gage 14 and draw-off 15, the latter being connected through the furnace wall with the lowest point of 40 the rear tube header so that the drum and tubes may be completely drained, as is well understood.

45 Leading from the still at an upward inclination is a combined vapor outlet pipe and reflux condenser or dephlegmator 16 of proper dimensions, and for increasing the

condensing capacity of the latter we preferably surmount it with a radiator 17. From the upper end of the radiator a vapor pipe 18 leads downwardly to a water-cooled condenser 19, and below the latter is arranged a receiving drum 20 for the condensate. It is to be noted that in the arrangement shown the entire system including the still, dephlegmator, radiator, condenser and receiving drum is in open communication throughout. The receiving drum is provided with a valved liquid drain 21 and a valved gas escape pipe 22, and by this construction the contents of the system may be brought to 55 and maintained at any desired pressure.

At the end of the dephlegmator 16 adjacent to the radiator 17 a supply pipe 23 is tapped thereinto which pipe may be split into two branches 24, 25, the former being 60 provided with a check valve 26 and control valve 27, and the latter, which is employed as a drain only, having a cut-off valve 28. The supply branch 24 will lead to a pump or storage chamber or reservoir having a 65 pressure sufficient for the introduction of the fluid into the dephlegmator, as will later appear.

Immediately below the elbow of the dephlegmator there is mounted within the 70 drum 10 a funnel 29 (Fig. 2) carried by an inclined pipe 30 which projects into the up-standing end 31 of the rear vertical trunk 32 by which the rear tube header is connected with the drum.

75 In the use of the apparatus above described for carrying out our new process, the still will be charged with a petroleum oil of relatively high boiling point, for instance a stock having a boiling point of its 80 lowest substantial fraction approximating 600° F. at atmospheric pressure. The still will then be fired and the contents heated up to a point at which distillation proceeds slowly under a pressure of upwards of four 85 and preferably about seven atmospheres, this pressure being maintained not only upon the liquid in the still but preferably also throughout the system under the control of the valved gas escape pipe 22, as in the 90 patent to William M. Burton, one of the present applicants, No. 1,049,667, of January 100

7th, 1913. The temperature of the liquid body and the vapors in the still will then be approximately 750° F., the temperature of the vapors being progressively less along 5 the length of the dephlegmator.

When this condition has been reached we begin to feed in through the supply pipe 24, a stock of oil of mean boiling point substantially lower than that of the stock in the 10 still, for instance "bottoms" from the redistillation of crude gasoline made by the process of the Burton patent before referred to. Such bottoms range in boiling point (at atmospheric pressure) from about 400° to 500° 15 or thereabouts. Under the pressure of seven atmospheres maintained in the still and its connected condenser the boiling point of this stock would be about 600° to 700° F., which would be too low to effect any considerable 20 cracking, especially since these "bottoms" have already been subjected to one cracking operation the result of which is to render them quite refractory.

As this cold stock, entering through the 25 pipe 24, passes downwardly through the dephlegmator and becomes mixed with the reflux condensate therein, its temperature is gradually raised, the rise being sufficient to bring the stream almost to its boiling point 30 at the time it leaves the lower end of the dephlegmator to drop into the funnel 29. The lighter portion of the mixed stream, including substantially all of the in-fed stock is thereupon instantly flashed into a vapor by 35 coming into contact with the hot body of oil. This vapor instead of remaining at its boiling-point temperature of 600° to 700°, becomes instantly superheated by the liquid body of the still charge and the high-boiling-point vapors thereof, being thus brought to the temperature of the still in spite of the fact that its normal boiling point temperature under the pressure obtaining in the still is materially below the temperature of 40 the latter. This superheating of the vapors of the low-boiling-point stock by the liquid body and vapors of distillation of the high-boiling-point stock, is the result aimed at by our process. Under these conditions the 45 temperature required for cracking the low-boiling-point material is obtained without the employment of proportionately high pressures, and without resort to superheating tubes, flash-plates, red-hot refractory 50 earth masses, molten metal baths, or any of the recognized expedients for superheating vapors. Whatever proportion of the mixed stream entering the funnel 29 fails to be vaporized therein is conducted directly downward into the hot tubes 10', being thereby 55 subjected immediately to the highest temperature available.

Our process may be carried out with the ordinary apparatus used for pressure distillation and therefore commends itself to

practical refiners as involving no untried expedients but only safe and economical methods of proven value.

It is to be noted that in the operation set forth above the charge of relatively high-boiling-point stock within the still is itself subjected to a cracking operation simultaneously with its use as a "superheater" for acting upon the lighter stock fed in. It will be apparent that the exact extent of this cracking of the still charge will depend upon the nature of that charge, i. e., it may be composed of such refractory constituents as to dissociate only to a small degree under the temperature and pressure conditions obtaining in the still, or it may be of such a nature as to crack at the ordinary rate under these conditions.

It will be understood that the cracked vapors of the in-fed stock will pass outwardly 25 through the dephlegmator, and thence to the condenser and receiving drum in the usual manner.

While we have described in considerable detail one specific manner of carrying out 90 the novel steps of our process, it is to be understood that this description is illustrative only, and for the purpose of making our invention more clear, and that we do not intend that our invention shall be construed 95 as limited to these details except in so far as we have included such limitations within the terms of the following claims in which it is our intention to claim all novelty inherent in our process as broadly as is permissible in 100 view of the prior art.

What we claim as new and desire to secure by Letters Patent is:

1. The process of distilling petroleum hydrocarbons which consists in heating a liquid body of such hydrocarbons above its atmospheric boiling point under a pressure of upwards of four atmospheres to effect distillation thereof, and feeding into such liquid body from an extraneous source a fresh stock 105 of hydrocarbon having a boiling point under the prevailing pressure lower than the temperature of the liquid body, thereby superheating and cracking the infed material.

2. The process of cracking refractory petroleum hydrocarbons which have previously undergone one cracking operation which consists in heating a liquid body of hydrocarbons having a boiling point above that of the refractory stock to a temperature exceeding the boiling-point of the latter, and introducing the refractory stock from an extraneous source into such heated mass, thereby superheating and cracking the same.

3. The process of distilling hydrocarbons for the pyrogenesis of lower boiling point hydrocarbons which consists in maintaining a body of the hydrocarbons in a receptacle under super-atmospheric pressure, and flowing a stream of said hydrocarbons through 130

a heated zone to said receptacle, thereby maintaining a vaporizing temperature in the receptacle, and supplying to said flowing stream from an extraneous source hydro-
5 carbons having a boiling point under the prevailing pressure lower than that of the body of hydrocarbons.

4. The process of distilling hydrocarbons for the pyrogenesis of lower boiling point hydrocarbons which consists in maintaining a body of the hydrocarbons treated in a receptacle under superatmospheric pressure, flowing a stream of said hydrocarbons through a heated zone to said receptacle, thereby maintaining a vaporizing temperature therein, cooling the vapors evolved to condense their heavier constituents and supplying this condensate to said flowing stream together with additional hydrocarbons from 20 an extraneous source having a boiling point under the prevailing pressure below that of the body of hydrocarbons.

5. The process of distilling hydrocarbons for the pyrogenesis of lower boiling point hydrocarbons which consist in maintaining a body of the hydrocarbons treated in a re-

ceptacle under superatmospheric pressure, flowing a stream of said hydrocarbons through a heated zone to said receptacle, cooling the vapors evolved to condense their heavier constituents, and supplying this condensate to said flowing stream. 30

6. The method of decomposing hydrocarbons for the pyrogenesis of lower boiling point hydrocarbons, which consists in maintaining a body of hydrocarbons treated in liquid state in a receptacle under superatmospheric pressure, flowing a stream of such hydrocarbons through a heated zone to said receptacle effecting a separation from 40 the treated hydrocarbons subsequent to their passage through the heated zone of constituents intermediate between the hydrocarbons treated and the desired low boiling products and supplying the intermediate 45 constituents to said flowing stream.
